ROELOF DE BOER AND HENRI WILLEM DE VOOGT, OF HEEMSTED, NETHERLANDS.

TRAILING NET.

Application filed April 11, 1924. Serial No. 705,921.

To all whom it may concern:

Be it known that we, ROELOF DE BOER and HENRI WILLEM DE VOOGT, both subjects of the Queen of the Netherlands, residing at 5 Heemstede, the Netherlands, have invented certain new and useful Improvements in Trailing Nets, of which the following is a specification.

The invention relates to trailing nets and 10 particularly to such nets to which by a special construction it is attempted to give a high and wide mouth opening.

Although the fundamental idea of the invention and the construction resulting therefrom relate to trailing nets along the ground (trawl nets) as well as to trailing nets which may be used along the surface or at an arbitrary depth beneath the surface, the following description will deal more particularly with trawl nets. In the numerous embodiments of trawl nets in which it is attempted to hold up a wide upper cable by floating bodies and thus increase the height of the mouth opening, the fact that the distance of the sheering boards (mouth width) is influenced by the forces acting in the vertical plane of the mouth opening and those acting in a horizontal plane has not sufficiently been taken into account.

30 In a vertical plane through the upper cable and sheering boards a state of equilibrium arises between the forces in this plane acting on the floating bodies and on the sheering boards.

35 In constructing the boards and corresponding floating bodies it is therefore of great importance to take into consideration the various forces acting on both in such a manner that the floating bodies at the normal speed come to stand perpendicularly above the boards.

The mutual distance of the floating bodies should determine as well as possible the distance between the corresponding sheering boards or the obtainable sheering width of the net. A single or more than two strong floating bodies arranged on the upper cable or the location of these floating bodies near the centre gives rise to an action of the net 50 which is undesirable for the fishery.

In the horizontal plane through the sheer-

ing boards the resistance which the net offers in the water and that which the heavy load in the waist exerts on the mutual distance of the boards will also give rise to a 55 state of equilibrium of the various forces. The strength of the force tending to move the boards towards each other is mainly dependent not only on the location of the above-mentioned floating bodies but on the 60 length of a single-waist net and on the resistance acting in the centre (the waist) and also on the length of the ground and upper cable.

The invention has for its object to construct a trailing net having a very wide mouth opening at the normal speed, on the one hand by choosing the point of application of the resistance of the net and the catch behind the boards in such a manner 65 that the component of this resistance, measured on the line connecting the boards, is as small as possible and, on the other hand, by connecting the floating bodies to the wide upper cable at the correct distance with regard to the sheering boards.

The invention consists in this, that two waists are provided, the vertical central planes of which are parallel or almost parallel to each other and to the trailing direction of the net and which central planes pass through the connecting points of the net to the sheering boards or intersect the connecting line of these boards at a mutual distance 80 smaller than that of the boards.

Now, according to the invention each waist may be connected by separate carrying lines to the sheering boards located in front of it. In this way, when trailing the net, the resistance caused by the waist in the water is 85 almost entirely received by the trailing line.

Moreover the meshes of the net leading to the waist are now not contracted when the waist is filled with fish and therefore the resistance of the net in the water is not increased. The inflowing water can easily escape through the open meshes. The net itself needs no more transmit the resistance of the waist to the sheering boards but the cables effect this and the net is not deformed.

100 Another feature of the invention consists in this, that the two waists are interconnect-

ed by a connecting line at the upper side of the net and a connecting line at the lower side, while on each of these connecting lines two points are connected to the sheering boards by upper and ground cable respectively.

The two connecting points of the connecting line with the upper cable may be provided with small floating bodies for lifting the back net.

Further, with a net of this kind, between the two sheering boards a second wide upper cable may be stretched to which two floating bodies are connected determining the mutual distance of the sheering board at the normal trailing speed.

By this construction, when trailing the net an almost rectangular mouth opening is formed; the tension in the horizontal portion of the cable between the two floating bodies and the horizontal component of the updriving force of these floating bodies balances the sheering force of the boards.

Between the wide upper cable and the back net, according to the invention convenient catching nets may be stretched while the floating bodies are preferably trailed by branch lines of the net trailing lines.

In order to make the net appropriate for trawling on stony (rocky) grounds according to the invention the net may be provided at the lower side with a pocket merging backwardly and laterally into the two waists and limited at the front side by a ground rope which may be provided with rolls or bobbins.

This modification of the net may be used as well for trawling herrings. In this case it is only desired to remove the bobbins from the ground rope and to suspend the net from surface floating bodies.

By shortening or lengthening the suspension lines the depth of the net below the surface of the water can be adjusted.

In the accompanying drawings, a trailing net according to the invention, constructed as a trawl net, is shown by way of example.

Figure 1 is a plan view of the net;

Figure 2 is a vertical longitudinal section, and

Figure 3 a front elevation.

Fig. 4 is a vertical longitudinal section of the net with pocket at the lower side for trawling herrings or for fishing on stony grounds.

Fig. 5 is a front elevation of this net.

The whole net is built up from a skeleton of carrying lines. The two waists 1 and 2 are each connected to the sheering boards 3 and 4 respectively by four carrying lines. The waist 1 is connected at the upper side by the lines 5 and 6 to the upper side of the sheering board 3 and by the lines 7 and 8 to the lower side of this sheering board. In a similar manner the lines 9, 10,

11 and 12 constitute the carrying lines for the waist 2.

Mutually the waists are connected at the lower and upper sides by two connecting lines that are of equal length. In Figure 1 70 the upper connecting line is indicated by the numerals 13, 14, and 15. The central portion 14 of this connecting line is connected at its ends by two upper cables 16, 17 to the sheering boards 3 and 4 respectively. 75 The central portion of the lower connecting line 18 is connected in a similar way by two ground cables 19 and 20 to the sheering boards 3 and 4. To the ends of the line 14 small floating bodies 21, 22 are, moreover, 80 connected for lifting the back net.

Moreover, by the above-described upper and ground cables, the sheering boards 3 and 4 are coupled in a substantially vertical plane by a wide upper cable 23. To this 85 upper cable two large floating bodies 24 and 25 are connected at such a mutual distance that when trailing the net these floating bodies are located above or approximately above the two sheering boards as indicated 90 in Figure 3.

The sheering force driving the boards away from each other is now received by the tension in the horizontal portion of the cable 23 while the updriving force of the 95 floating bodies 24 and 25 determines the tension in the downwardly running parts of this cable connecting the floating bodies to the centres of the sheering boards. The floating bodies 24 and 25 are moreover connected by cables 32 to the upper back side 100 of the sheering boards.

The floating bodies 24 and 25 are trailed by the branch lines 26 of the trailing lines 27 of the net.

The triangular portions formed by the various lines of the skeleton are closed in by a net in the usual way. Between the upper connecting lines 13, 14, 15 of the waists and the lower connecting line located underneath a pouch shaped net is stretched. This pouch net 28 forms a transition between the front net and the two waists.

The points of the line 14, to which the floating bodies 21 and 22 are attached, are 115 connected by two lines 29 and 30 (see Figure 3) to the points of cable 23 under the floating bodies 24 and 25. The trapezium-shaped plane between the lines 23, 14, 16 and 17 is filled in by a net; equally the 120 triangular planes formed by the lines 30 and 16 on the one hand and 29 and 17 on the other hand, with the corresponding vertical portions of cable 23.

Finally, reference is directed to the 125 wakening chain 31 which may be stretched in front of the ground cable between the sheering boards.

In the net according to the invention it is only the resistance of a small portion of 130

the net itself that counteracts the sheering action of the boards; the resistance of the waists has no material influence thereon.

When the net is used for trawling on stony grounds then at the lower side a pocket may be provided as shown in Figs. 4 and 5. The shape and the connection of this pocket to the net appears sufficiently from the drawings. It corresponds chiefly to the upper portion of the net. 33 constitutes the ground cable which may be weighted or provided with rolls. The waists may be lifted by floating bodies 36. For trawling herrings the floating bodies 24 and 25 are connected by cables 34 to floating bodies 35 at the surface. The net is thereby lifted at the front side and an opening is formed from the ground cable 33 to the horizontal upper cable 23. By shortening or lengthening the suspension lines 34 the depth of the net under the water level may be adjusted.

Having now particularly described and ascertained the nature of our said invention 25 and in what manner the same is to be performed, we declare that what we claim is:—

1. An improved trawl net having two otterboards and two waists, the vertical central planes of which pass practically through 30 the connecting points of the net to the otterboards.

2. An improved trawl net having two otterboards and two waists, the vertical central planes of which pass practically through 35 the connecting points of the net to the otterboards and each of which waists is directly connected by separate carrying lines to the otterboard located in front of it.

3. A trawl net having two waists, each of 40 which is directly connected to the sheering board located in front of it, and interconnected by a connecting line at the upper side and a connecting line at the lower side of the net, while two points on each of these 45 connecting lines are connected by upper and ground cables respectively to the sheering boards.

4. A trawl net as claimed in claim 3 having floating bodies provided to the two connecting points of the connecting line with the upper cables.

5. A trawl net having two waists, the vertical central planes of which are practically parallel to each other, and a wide upper cable stretched between the sheering boards provided with two floating bodies at a mutual distance practically equal to the distance of the sheering boards at a normal trailing speed.

6. A trawl net having two waists, each of which is directly connected by separate carrying lines to a sheering board, and a wide upper cable stretched between the sheering boards provided with two floating bodies at a mutual distance practically equal

to the distance of the sheering boards at a normal trailing speed.

7. A trawl net having two waists, each of which is connected separately to a sheering board and interconnected at the upper and 70 the lower side of the net whereas a wide upper cable is stretched between the sheering boards, provided with two floating bodies at a mutual distance corresponding to the distance of the sheering boards at a 75 normal speed of trailing.

8. A trawl net having two waists and means for connecting said waists to the sheering boards and one to the other, whereas the mutual connecting lines of the waists 80 are connected to the sheering boards at the upper and lower side of the net by upper- and ground ropes respectively, and wherein between the sheering boards of the net a second wide upper cable is stretched, to 85 which two floating bodies are connected at a mutual distance practically equal to the distance of the sheering boards at a normal trailing speed.

9. A trawl net having two waists, lines for 90 connecting said waists to the sheering boards and one to the other and lines for connecting two points on the upper mutual connecting line of the waists to the sheering boards, which two points are provided with 95 floating bodies, whereas a wide upper cable is stretched between the sheering boards having two floating bodies at a mutual distance corresponding to the distance of the sheering boards at a normal trailing speed, and 100 trailed by branches of the net trailing ropes.

10. A trawl net having a wide upper cable stretched between the sheering boards, provided with two floating bodies, and two waists connected to the sheering boards and 105 interconnected by lines at the upper and the lower side of the net whereas each of two points of the upper interconnecting line is connected to a sheering board and to a point of the wide upper cable to which a 110 floating body is attached.

11. A trawl net having two waists, the vertical central planes of which are practically parallel to each other and a wide upper cable stretched between the sheering board and 115 provided with two floating bodies trailed by branches of the net trailing ropes.

12. A trawl net having two waists, each of which is directly connected to the sheering board located in front of it and two pocket shaped secondary parts respectively located at the upper and at the lower side of the main net the first one being limited at the front side by a wide upper cable (23) 120 stretched between the sheering boards and provided with two floating bodies (24, 25) suspended from surface floats (35) and trailed by branches of the net trailing ropes, the latter limited at the front side by a ground rope (33). 125 130

13. A trawlnet having two waists, each of which is directly connected to the sheering board located in front of it and two pocket shaped secondary parts respectively located at the upper and at the lower side of the main net the first one being limited at the front side by a wide upper cable (23) stretched between the sheering boards and

provided with two floating bodies (24, 25) trailed by branch lines of the net trailing 10 ropes, the latter limited at the front side by a ground rope (33).

In testimony whereof we affix our signatures:

ROELOF DE BOER.

HENRI WILLEM DE VOOGT.
